HAND WEAPON

Robert B. Hutchison, Wilkinsburg, Pa.; Ella J. Hutchison and Mary W. Hutchison, executrices of Robert B. Hutchison, deceased, assignors to Clarence A. Williams

Application June 5, 1933, Serial No. 674,446
Renewed January 14, 1939

10 Claims.

(Cl. 42—1)

This invention relates to firearms, particularly to firearms of the combined club and gun type having self contained means for firing shells or cartridges.

5 An object is the provision in a weapon of this character, of means for firing a plurality of charges in sequence without reloading between discharges.

10 Another object is the provision in such a weapon, of firing mechanism selectively operable to function either as single action or repeater action.

15 Another object is the provision of a weapon of this character wherein the entire charge holding and firing mechanism assembly is arranged as a quick detachable removable unit.

20 The present disclosure constitutes the best means I have thus far devised in reducing the invention to practice. It is to be understood however, that various structural embodiments of the principles may be employed, within the scope of the invention as claimed.

25 In the disclosed embodiment the invention is shown as a police club or billy, adapted to be used as a gas projecting weapon, capable of firing a large charge of incapacitating gas for riot service, or of firing in sequence a plurality of smaller charges for use against individuals and in situations where a heavy charge is neither required nor desirable.

30 In the drawings:

Figure 1 is a perspective view of the billy.

Figure 2 is a longitudinal section therethrough.

Figure 3 is a section on line 3—3 of Figure 2.

35 Figure 4 is a section on line 4—4 of Figure 2.

Figure 5 is a fragmentary longitudinal section, at a right angle to the section of Figure 2, with the firing mechanism in elevation.

40 Figure 6 is a fragmentary perspective of a firing mechanism unit.

Figure 7 is a fragmentary perspective of a multiple cartridge holder.

Figure 8 is a section on line 8—8 of Figure 2, illustrating the set of the firing mechanism for repeater action.

Figure 9 is a similar section, with the firing mechanism set for single action.

Figure 10 is a group perspective of the firing rod and the adjustable cam by which the weapon is selectively set to fire as single action or as repeater action.

Figure 11 is a fragmentary section substantially as in Figure 2, and illustrating the use of an adapter holding a single large charge shell or cartridge.

Figure 12 is a fragmentary section illustrating the use of multiple nesting adapters for accommodating shells or cartridges of varied calibers.

Figure 13 is a fragmentary section illustrating the use of an alternative embodiment of charge holding means.

Figure 14 is a section on line 14—14 of Figure 13.

Figure 15 is a perspective of the butt end of the barrel portion.

Figure 16 is a section on line 16—16 of Figure 2.

In detail, the weapon comprises a barrel, which functions also as a club, consisting of a tube 17 of aluminum or other suitable material externally threaded at its muzzle end to receive an end ring 18 that is shouldered to provide an end stop for a casing 19 of pressed leather washers, or other suitable material surrounding the tube and abutting an aluminum stop ring 20 press fitted to the tube adjacent its butt end.

At the butt end the tube 17 extends beyond the stop ring 20 to provide a hand grip portion in cooperation with other elements to be described. Tube 17 is of uniform diameter throughout its extent. The bore of the barrel is determined however, by the provision of an inner tube 21 riveted to tube 17 and extending inwardly from the muzzle end a distance sufficient so that its inner end provides a stop shoulder 22 for seating the discharge end of a charge holding magazine, shown in Figures 2, 5 and 7 as a cylinder 23 provided with a plurality of radially arranged cartridge chambers 24, being three in number in the illustrated embodiment. A series of aligning studs 25 project from the loading face of the cylinder, which face is further provided with an axial idler socket 26, having a purpose later detailed. The cylinder 23 is freely slidable in tube 17 being insertable and removable through the butt end thereof.

In the cartridge cylinder 23 the chambers 24 are coextensive with the length of the cylinder. An alternative embodiment of cylinder is shown in Figures 13 and 14. In this form the discharge end of each chamber 24 is internally threaded for the attachment therein of an auxiliary barrel 27 extending through tube 21 to the muzzle of the weapon, the three barrels being supported at the muzzle by a spider 28.

The firing unit of the weapon comprises a tube 29 of aluminum or other suitable material slidably insertable in tube 17, and which is threaded at the butt end onto an end plug 30 rotatably carried on a smaller concentric tube 31 having

its butt end threaded into an operating member such as a knob or cap 32. The plug 30 is disposed between the operating member 32 and a cross pin 33 which extends across the bore of the tube 31 and serves as a holding abutment for one end of the main firing spring 34.

This spring 34 is a coiled expansion spring which is housed in the bore of tube 31 and bears against one end of a firing rod 35 slidably carried in tube 31 and projected therefrom by the main firing spring 34. A lateral stud 36 working in a longitudinal slot 37 aligns the firing rod and limits the extent of its movement under the influence of camming means to be described. Adjacent its outer end the firing rod 35 is provided with a lateral firing stud 38.

Beyond the end of the firing rod the housing tube 29 is provided with a firing pin support assembly comprising a pair of spaced annular plugs 39 and 40 rigidly anchored to the tube by securing elements 41 and 42 respectively. The plug 39 adjacent the firing rod has slidably mounted therein the shank of a central firing pin 43 disposed in coaxial alignment with the firing rod 35. Between the support plugs 39 and 40 the firing pin shank is provided with a shoulder 44 beyond which it is reduced to form a striker 45 slidably disposed through the plug 40.

Arranged in mutually spaced relation radially about the central firing pin are a plurality of similar firing pins, here shown as three, with their shanks 46 slidable through the plug 39 and their reduced strikers 47 slidably supported in the end plug 40. These pins also carry each a shoulder 48 in the space between the support plugs. Expansion springs 49, coiled about the shank of each firing pin striker portion between the shoulders 46, 48 and the inner face of the end plug 40 serve normally to hold the firing pins in retracted position, with their striker points housed entirely within plug 39.

Seated against the inner face of the plug 39 is a cam sleeve 50 formed as a crown cam with risers 51 terminating abruptly at the edges of valleys 52. This cam is circumferentially shiftable on the inner wall of tube 29 into two positions of adjustment, indicated and determined by the setting of a thread bolt 53, the shank of which is slideable in a peripheral slot 54 of tube 29. At each end of the slot the tube is stamped or otherwise provided with indicia, see Figure 6, to indicate the cam setting for single action firing, or repeater action for a plurality of charges. Bolt 53 is threaded in a socket 55 of the cam and upon being threaded home at either countersunk end of slot 54 the bolt head clamps on tube 29 to anchor the cam in its setting.

As shown in Figure 15, the butt end of barrel tube 17 is provided with radially disposed end opening bayonet slots 56 arranged to take internally projecting studs 57 carried by a guard sleeve 58 threaded at one end onto the butt plug 30 and arranged to slide over tube 17 to abut the stop ring 28 at its other end. Sleeve 58 serves as a hand grip portion for the weapon.

Inasmuch as guard sleeve 58, butt plug 30, and sleeve 29 with its associated firing pin support assembly are rotated as a unit relative to the barrel tube 17 in inserting and securing the firing mechanism, means are provided for latching the unit in attached position. This latch means consists of a spring detent 59 secured to the external wall of the guard sleeve and having a holding stud 60 disposed through an aperture provided through the sleeve through which the stud is

seated in a socket 61 formed by enlarging an end of one of the bayonet slots 56 of the barrel tube 17. The diameter of stud 60 corresponds to that of its socket 61, which is greater than the width of the bayonet slot, so that when the stud is engaged in the socket the parts are latched against relative rotary movement.

In those instances wherein it is desired to employ the weapon for the firing of single shells or cartridges, the magazine cylinder is replaced by an adapter sleeve 62, as shown in Figure 11, for holding a single shell or cartridge 63 of large caliber. By utilizing a concentric nesting adapter sleeve 64, Figure 12, seated within the adapter 62, a smaller caliber single shell 65 may be fired. It will be understood that this principle of nesting adapters may be carried out in any desired number, whereby the weapon can be utilized to fire a charge of any caliber shell or cartridge.

In service, the weapon is fired by grasping the club portion 19 in one hand and rotating the knob 32 in a clockwise direction with the other.

When firing as a repeater to discharge in sequence the cartridges 66 with which the cylinder magazine is loaded, the selective control cam 58 is set, as shown in Figure 6 to the plural firing position. This setting disposes the cam valleys 52 in longitudinal alignment with the three shanks 46 of the firing pins, as best shown in Figure 5. Then as firing knob 32 is rotated the stud 33 of firing rod 35 rides inwardly on a cam riser, retracting the firing rod against compression of its spring 34. When the stud clears the abrupt edge of the riser the spring 34 immediately projects the firing rod forwardly; contacting and actuating the central firing pin 43, and at the same time the firing stud 38 contacts and actuates the adjacent firing pin 46, firing the cartridge in the magazine chamber which is aligned with the striker of the firing pin thus actuated.

As the firing knob is again rotated the operation is repeated through engagement of the firing stud 38 with the next cam riser to fire a second cartridge; the same action being repeated to fire the third cartridge. During this repeater action firing, the central firing pin 43 idles, its striker entering the idler socket 26 each time the pin is actuated. Figure 8 further illustrates the cam setting for the repeater action described.

When the weapon is to be used for the firing of a single charge, of larger capacity, as in Figures 11 and 12, the selective cam control 50 is set at single action position by appropriately shifting the cam, as shown in Figure 9, so that the cam valleys do not align with the shanks of the firing pins. Under this setting of the firing mechanism, as the firing knob 32 is rotated only the central firing pin 43 is actuated by the firing rod, for although the same engagement of the firing rod stud 33 and cam risers takes place, the stud clears the outer pins each time it snaps forward into a cam valley.

In assembling the weapon, as for firing a plurality of charges without reloading, the magazine cylinder 23 is loaded with cartridges, one being shown in elevation in Figure 2, and the selective cam control is set for repeater action as previously described. The magazine and firing unit are then connected by inserting the magazine aligning pins 25 in receiving sockets 67 provided in the outer firing pin support plug 40, Figure 6. The assembly of magazine and firing unit is then inserted in the barrel tube 17 from its butt end with the studs of guard sleeve 58 engaging the

bayonet slots 56. The guard sleeve is then turned to secure the bayonet connection and to seat the latch stud 60 in socket 61.

In disassembling, the guard sleeve is turned to release the bayonet slot connection, after which the entire firing unit housed in the tube 29 may be withdrawn from the barrel tube. The magazine cylinder is slidably removable simply by inclining the barrel to permit the cylinder to drop through the butt end.

As hereinbefore described, the magazine may be replaced by an adapter tube for firing a single charge, in which case the selective cam control is set at single action position.

15 I claim:

1. A firearm comprising a club provided with an axial barrel, charge holding means adapted to be inserted therein, charge firing means insertable in said barrel, means for selectively adjusting said firing means to one position to operate as a combined single action and repeater action and to another position as single action only, and means for holding said charge holding means and said firing means in service position within 25 the barrel.

2. A firearm comprising a club provided with an axial barrel, charge holding means slidably insertable therein, charge firing mechanism insertable in said barrel and including a plurality of 30 firing pins, means for actuating said pins, and means for shifting the relative positions of the firing pins and actuating means.

3. In a firearm, a barrel, a firing unit detachably insertable therein, and means shiftable 35 within said unit for adjusting said unit to operate as a single action mechanism or as a repeater action mechanism.

4. A firing unit for club guns, comprising a barrel insertable tube, a butt plug closing said 40 tube at one end, a firing pin support plug in the other end thereof, a central firing pin carried by said support plug, a plurality of firing pins in said plug and disposed in a circle concentric with said center pin, a firing rod for actuating said 45 pins, and means selectively adjustable to cause the firing rod to actuate either the center pin only, or to actuate said pins in pairs including the center pin.

5. In a firearm, a spring projected firing rod, 50 a firing pin coaxial therewith and actuated thereby, a lateral stud on said rod, a firing pin spaced from said first named pin and adapted for actuation by said stud, and means for determining the path of travel of said stud, said means being selectively adjustable either to guide said stud into

actuating contact with the second named firing pin or to guide said stud past said pin without contact.

6. In a firearm, a barrel, a tube slidably insertable therein from the butt end, a plurality 5 of firing pins carried by said tube, a single firing rod in said tube for actuating said firing pins, means for projecting said firing rod into actuating contact with said pins, and means adjustable within said tube for selectively guiding said 10 rod to actuate only one firing pin in one position of adjustment and to actuate a plurality of the pins in another position of adjustment.

7. In a firearm, a firing unit comprising a central firing pin, a series of outer firing pins 15 arranged in a circle concentric with the axis of the central pin, a spring projected firing rod adapted to actuate said pins by striking contact, and means adjustable to one position for serially actuating the outer firing pins from said rod, and 20 to another position for actuating only the central firing pin from said rod.

8. A firearm comprising a club provided with a single axial barrel, a charge holding magazine 25 slidably insertable therein, means for preventing any rotation of said magazine within the barrel, and means for successively firing the charges in said magazine through said barrel.

9. A firearm comprising a club provided with an axial barrel, charge holding means slidably 30 insertable therein, charge firing mechanism insertable in said barrel behind the charge holding means and including a plurality of firing pins, means for holding said firing pins and charge holding means against rotation with respect to 35 the barrel, means for actuating the firing pins, and means for shifting the actuating means with respect to the firing pins whereby to actuate the firing pins singly or as radial pairs.

10. A firearm comprising a club provided with 40 an axial barrel, charge holding means slidably insertable therein, charge firing mechanism insertable in said barrel behind said charge holding means and including a hollow tube provided with axially spaced partition plugs, a plurality of firing pins supported in said plugs in circumferentially spaced relation and axially slidable there-through, means between said plugs and normally retracting said firing pins, a central firing pin 45 slidable axially through said plugs, means for actuating the firing pins, and means for shifting the actuating means with respect to the firing pins whereby to actuate the firing pins singly or as radial pairs.

ROBERT B. HUTCHISON. 55
